UNITED STATES PATENT OFFICE.

MORRIS S. FINKELSTEIN, OF NEW YORK, N. Y.

LOCK.

Application filed February 28, 1922. Serial No. 539,868.

To all whom it may concern:

Be it known that MORRIS S. FINKELSTEIN, a citizen of the United States, and a resident of New York city, in the county of 5 New York and State of New York, has invented certain new and useful Improvements in Locks, of which the following is a specification.

My invention relates to locks, and the 10 object of my invention is to provide a lock suitable for doors which swing on hinges and open inwardly.

A further object is to provide a lock having a main bolt controlled by one key and 15 a second bolt adapted to engage the main bolt and controlled by an independent key.

A further object is to provide a lock, the main bolt of which is adapted to be connected in co-operative engagement with one 20 end of a brace bar which extends to the floor to brace the door when closed and locked.

A further object is to provide means for carrying the brace-bar on the door when the 25 door is open.

A further object is to provide means to carry said bar to one side to permit free ingress when the door is being opened.

Referring to the drawings which form 30 a part of this specification,

Figure 1 is a front elevational view showing a portion of the inner side of a door with the improved lock mounted thereon and the back plate removed, and the door 35 jam carrying the co-operative portions, the lock being in unlocked position.

Figure 2 is a similar front view showing the position of the brace-bar when the door is locked, and the safety chain connected to 40 the door.

Figure 3 is an exterior view showing the brace-bar carried by the main bolt into locked position together with the main bolt.

Figure 4 is an inverted end view of the 45 lock showing the brace-bar in cross section and main bolt in locked position.

Figure 5 is a side elevational view of the door with the brace-bar set in locked position.

Figure 6 is a side view showing the top 50 of the brace-bar held by the guard.

A, indicates a door which opens inwardly and A' the door jamb. B, indicates the lock frame in which is formed a guiding slot C for the main bolt D which extends longitudinally. The main bolt D is provided

with two vertically extending slots D' and E respectively. The slot D' is adapted to receive a vertically movable bolt F controlled by a separate lock and key G, and the slot E is adapted to receive the upper end of the brace-bar H and carry it under the plate I in its locking movement. This movement carries the slot D' into alignment with the bolt F which is then thrown by the locking part G into engagement to lock the main bolt in locked position. The main bolt is controlled by the lock J operated in the usual manner by a key J'. The lock G is also of the usual type and operated by a key G' but the bolt F is provided with two indentations K and K' respectively to receive a holding pin L held in operative arrangement by a spring M, the object of this arrangement being to hold the bolt in its locked or unlocked position against the action of gravity.

It will be observed that the back-plate of the frame B projects beyond the edge of the door A adjacent the door jamb A' and overlaps the jamb-plate A² which plate is provided with a vertically extending projection A³ which is overlapped by an inwardly extending projection B' formed on the frame of the main lock. This construction prevents the main bolt from being easily reached since the lock frame would have to be cut away before the bolt could be reached with a saw or chisel. The end of the main bolt D is held by the plate A² on which is formed the usual lock member A³ into which the end of the bolt projects. For convenience in locking the door from the inside a knob controlled latch lever A⁵ controlled by a knob A⁴, is adapted to engage the projections N—N respectively formed integral with the bolt F. By rotating the knob the bolt F may be moved in the desired direction. A plate O carried on the frame overlaps the lower end of the bolt F to guide and hold the same. Carried on the bottom of the door is a socket P to hold the lower end of the brace-bar when the door is open, the upper end of said bar being held by the loop Q which swings from its supporting hinges R—R respectively one of which is located at each side of the channel S. This channel extends from the plane surface S' to the upper surface S² of the frame and is curved as illustrated by the dotted line S³ of Figure 5. T, indicates a chain, one end of

which is connected to the brace-bar near its upper end as illustrated in Figure 1, and the other end is connected to the plate A². V, indicates a safety chain, one end of 5 which carries an anchor-pin V' the head V² of which may be inserted in the opening V formed in the frame plate B and thence under said plate as illustrated to hold it in 10 detachable relation. The opposite end of 10 the chain is held to the plate A² by a plate W in which the holding pin W' is held in 15 swiveling relation. X, indicates a floor socket into which the lower end of the brace-bar projects and which forms a substantial abutment for said bar.

The lock is operated as follows:

Assuming the door A to be open. The operator removes the brace-bar from the door after swinging guard Q into its upper 20 open position and connects the free end of the chain T to the ring T', and then places the lower end of the brace-bar in the socket X and rests the upper end against the plate A² after which he passes through the door- 25 way and swings the door until it is nearly closed, then reaches inside and swings the top end of the brace-bar into channel S of the lock and thereafter closes the door.

The upper lock is then operated by the 30 key J' which causes the latch-bar J² to enter the slot J³ in its rotational movement and throw the main bolt into locked position and thus carrying the upper end of the brace-bar under plate I and bringing 35 its upper end under the abutment Y of the lock frame. The key G' is then used to move bolt F into the slot D', the latch lever G' entering the slot F' of the bolt F in 40 its rotational movement and thus completing the locking operation.

In order to open the door the lock G is first operated and then lock J after which

the door is opened and the top of the brace-bar is automatically drawn out of the channel S by engagement with the curved portion S³ of said channel and swung to one side by chain T.

When locking from the inside the bolt F is operated by the knob A⁴ and the safety chain V attached in the usual way.

Having thus described my invention I claim as new:—

1. A lock comprising a frame having a main bolt adapted to be operated by a key and a second bolt adapted to hold said main bolt in locked position and a brace-bar carried into locked position by said main bolt and means for automatically withdrawing said brace-bar from said lock when the door is being opened.

2. A lock comprising a frame having a main bolt adapted to be operated by a key and a second bolt adapted to hold said main bolt in locked position and a brace-bar carried into locked position by said main bolt and means for carrying said brace-bar on said door.

3. A lock comprising a frame having a main bolt adapted to be operated by a key, a brace bar adapted to be carried into locked position by said main bolt, said brace bar cooperating with a groove having an inclined portion leading therefrom, a chain attached to said brace bar and to the frame of the door whereby when the door is opened, the brace bar rides out of said groove on the inclined portion thereof and is pulled aside by said chain.

Signed at New York in the county of New York and State of New York this 15th day of February A. D. 1922.

MORRIS S. FINKELSTEIN.

Witness:

FRANK M. ASHLEY.
